(57) **CLAIM**

The ornamental design for a garment air hose connector, as shown and described.

DESCRIPTION

FIG. 1 is a perspective exploded view of the invention showing the nozzle, disk, and spike parts separated.

FIG. 2 is a perspective view of the assembled invention.
FIG. 3 is a perspective view of the assembled nozzle and disk parts of the invention.

FIG. 4 is a perspective view of the assembled nozzle and spike parts of the invention.

FIG. 5 is a side elevational view of the nozzle part of the invention.

FIG. 6 is a front elevational view of the nozzle part of the invention.

FIG. 7 is a bottom plan view of the nozzle part of the invention.

FIG. 8 is a top plan view of the nozzle part of the invention.

FIG. 9 is a top plan view of the spike part of the invention.

FIG. 10 is a side elevational view of the spike part of the invention.

FIG. 11 is a bottom plan view of the spike part of the invention.

FIG. 12 is a bottom plan view of the disk part of the invention.

FIG. 13 is a side elevational view of the disk part of the invention.

FIG. 14 is a top plan view of the disk part of the invention; and,

FIG. 15 is a perspective view of the invention showing the environmental structure of an air hose and garment.

The claimed design encompasses multiple parts within a single entity of manufacture. The claim is directed to the collective appearance of the parts in the combination shown. The parts are shown separately in FIG. 1 for clarity of illustration, and the bracket embracing the separate parts forms no part of the claimed design. FIGS. 3-15 show fewer than all of the parts of the claimed design for clarity of illustration.

Broken lines in the drawings are used to illustrate the environmental structure in which the article embodying the design is used. The environmental structure forms no part of the claimed design.

The left and right sides of the nozzle part of the invention are identical, and thus only a single side is shown in the drawings. The front and back of the nozzle part of the invention are identical, and thus only the front is shown in the drawings.

(Continued)

The spike part of the invention is identical as viewed from all sides, and thus only a single side is shown in the drawings.

The disk part of the invention is identical as viewed from all sides, and thus only a single side is shown in the drawings.

1 Claim, 5 Drawing Sheets
